UNITED STATES PATENT OFFICE.

JOHN GILLAM SMITH, OF KELTONBURG, TENNESSEE.

CHURN.

No. 811,102.

Specification of Letters Patent.

Patented Jan. 30, 1906.

Application filed August 4, 1905. Serial No. 272,665.

to all whom it may concern:

Be it known that I, JOHN GILLAM SMITH, a citizen of the United States, residing at Keltonburg, in the county of Dekalb and State 5 of Tennessee, have invented certain new and useful Improvements in Churns; and I do declare the following to be a full, clear, and exact description of the invention, such as will enable others skilled in the art to which it app- 10 pertains to make and use the same, reference being had to the accompanying drawings, and to the figures of reference marked thereon, which form a part of this specification.

My invention relates to churns, and has 15 for its object to provide a rotary churn which employs a jar or receptacle preferably of glass or stone.

With this object in view my invention consists in providing a frame which may be ad- 20 justed to fit jars or receptacles of different sizes, so that should the jar or receptacle break or become unfit for use the same can be removed and a new jar or receptacle of the same or a different size can be substituted.

25 My invention also consists in certain combinations or parts which will be first fully described and afterward specifically pointed out in the appended claim.

Referring to the accompanying drawings, 30 Figure 1 is an elevation showing churn in position on stand. Fig. 2 is a perspective view of adjustable frame or bands. Fig. 3 is a perspective view of adjustable cap or head securing portion of frame, and Fig. 4 is a vertical section through cap or head and upper portion of jar or receptacle.

Like numerals of reference indicate the same parts throughout the several figures, in which—

35 1 indicates the churn, which comprises the stand 2, formed, preferably, as shown in Fig. 1, the jar or receptacle 3, and the frame 4.

Referring particularly to Fig. 2, it will be seen that the frame comprises two open bands 5, which open bands carry an angle-plate 5', which is secured to the bands by a small bolt 5'', the said bands being provided with a series of perforations 5''' on one end thereof in order to accommodate the bolt 5'', 45 thus allowing a large range of adjustment, the ends being secured together by screws 6. Arranged in the bands 5, as shown in Fig. 2, are a series of perforations 5'', and one of the side pieces 7 is provided with a screw or bolt 7', 50 which is designed to pass through the perfora-

ration 5''' to adjust the side piece 7 on the bands 5, so as to cause the said side pieces 7 to be exactly opposite each other when the bands 5 are adjusted on the jar or receptacle.

7 indicates the side pieces which connect 60 the two bands 5 together, said side pieces 7 carrying the journals 8, one of said journals 8 being provided with a square end 9 to accommodate a crank 10, as shown in Fig. 1.

11 indicates the cap or head securing portion 65 of the frame, the sides 12 of said portion being provided with a series of perforations 13, as shown in Fig. 3, and 14 indicates a screw provided with a handle 15, said screw threading through the top of the cap or head 70 securing portion, as shown.

16 indicates the cap or head of the jar or receptacle which comprises, preferably, two layers 17 of wood and an inner layer of cork 18, and, if desired, a thin covering of rubber 75 17 can be employed.

Having thus described the several parts of my invention, its operation is as follows: The stand 2, as shown in dotted lines in Fig. 1, is provided with a groove within which the 80 journals 8 of the frame rest, so that the churn may be readily lifted off the stand 2. The jar or receptacle 3 is placed within the rings 5, and the said rings are secured about the jar or receptacle by means of the screws 6. When 85 the jar is thus in position, the cap or head engaging member 11 is passed on the journals 8, said journals entering the perforation 13, a number of perforations 13 being provided, so as to lengthen or shorten the said cap or head 90 engaging member in order to conform to the length of the jar or receptacle. After the milk has been placed in the receptacle the cap or head is placed in position and the screw 14 is turned, so as to securely engage 95 the said cap or head to hold the same firmly in position. The entire device is then rotated by means of the crank 10, and when the butter is ready to be taken from the churn the same may be tilted or the entire churn may 100 be removed from the stand 2, as desired.

Having thus fully described my invention, I do not wish to be understood as limiting myself to the exact construction as herein set forth, as various slight changes may be made 105 therein which would fall within the limit and scope of my invention, and I consider myself clearly entitled to all such changes and modifications.

What I claim as my invention, and desire 110

to secure by Letters Patent of the United States, is—

In a device of the character described, the combination of two open bands and means for adjusting the same, side pieces connecting said bands together, journals carried by said side pieces, a cap or head engaging portion provided with perforations and arranged to be passed on the said journals on said side pieces, and a screw carried in said cap or head

engaging portion arranged to engage the cap or head of the receptacle, substantially as described and for the purposes set forth.

In testimony whereof I affix my signature in presence of two witnesses.

JOHN GILLAM SMITH.
